(57) **CLAIM**

The ornamental design for a nail art device, as shown and described.

DESCRIPTION

FIG. 1 is a front and bottom perspective view of a nail art device, showing my new design;

FIG. 2 is a rear and top perspective view thereof;

FIG. 3 is a front elevation view thereof;

FIG. 4 is a top plan view thereof; and,

FIG. 5 is an enlarged view of a portion in FIG. 1.

The dash dot dash lines in FIGS. 1 and 5 are for the purpose of depicting the boundary lines of the enlarged view and form no part of the claimed design.
